[57] **CLAIM**

The ornamental design for a deployable monitor, as shown and described.

DESCRIPTION

FIG. 1 is a front elevational view of a deployable monitor, the broken line drawing of a vehicle glove compartment is for illustrative purposes only and forms no part of the claimed design;

FIG. 2 is a rear elevational view of the deployable monitor of FIG. 1;

FIG. 3 is a right-side elevational view, the left-side view is a mirror image thereof, the broken line drawing shows the monitor portion in alternate positions; and,

FIG. 4 is a bottom view thereof.
